His ATTORNEY.

UNITED STATES PATENT OFFICE.

JAMES E. MARSHALL, OF CLEVELAND, OHIO, ASSIGNOR TO GENERAL ELECTRIC COMPANY, A CORPORATION OF NEW YORK.

APPARATUS FOR SHAPING FILAMENTS.

1,298,533.

Specification of Letters Patent. Patented Mar. 25, 1919.

Application filed May 10, 1916. Serial No. 96,727.

To all whom it may concern:

Be it known that I, JAMES E. MARSHALL, a citizen of the United States, residing at Cleveland, Cuyahoga county, State of Ohio, 5 have invented certain new and useful Improvements in Apparatus for Shaping Filaments, of which the following is a specification.

My invention relates to an apparatus for 10 shaping wire, as coiled tungsten lamp filaments, according to the method set forth in pending Hughes application Serial No. 61,408, filed November 13, 1915.

The object of my invention is to provide 15 an apparatus whereby the filaments may be shaped or crimped in a sure and reliable manner, with a minimum of labor and with great facility, and in accordance therewith the filaments, which have been previously 20 prepared for the crimping operation, are fed, preferably one by one, into a receptacle or special hopper located above horizontally disposed shaping rollers and from this receptacle the filament lengths are caused to 25 fall transversely of their lengths between the horizontally disposed crimping rollers. The rollers are actuated, preferably intermittently, to crimp and deliver the filaments to a suitable receptacle and are made ad- 30 justable toward and away from each other to regulate the degree of crimping.

My invention will be more particularly pointed out in the description of the following drawings which form one complete embodiment of my invention, and in the attached claims.

Figure 1 is a perspective view of my apparatus; Fig. 2 is a view of the rollers with one in section; Fig. 3 is a plan view; Fig. 4 40 is a side view; and Fig. 5 is a view of a filament length before and after the crimping operation.

Referring to the drawings, suitable standards 1, carried by a base 2, support a platform 45 3 for receiving the prepared filament lengths. The standards carry near their upper ends a roller 4, suitably journaled therein, which cooperates with a roller 5 to shape and crimp the filament lengths. The roller 5 is journaled on a standard 6 and this standard is mounted in a trunnion 7 for adjusting the roller 5 toward or away from the roller 4. The adjustment is brought about by means of adjustable nuts 8 on tie rods 9, the rods 55 being pivoted at one end on standards 1 and

passing through ears on the standard 6. The crimping rollers are actuated in the manner now described. The roller 4 is geared to a ratchet wheel 10 through meshing gears 11, the larger gear 11 being on the shaft of ratchet 10. This shaft has loosely mounted on one end thereof an actuating lever 12 which carries a pawl, as indicated, for actuating the ratchet. The standard 6 carries on a bracket at right angles thereto a pivoted 60 framework 13, the upper part of which cooperates with platform 3 to form a trough or gutter-like receptacle or hopper 14. Normally the frame-work 13 is urged in a clockwise direction by means of a spring 15, 65 thereby closing the hopper. The framework 13 is connected to actuating lever 12 through a crank arm 16 and the rod 17, the free end of the latter engaging a shoulder on the short end of the lever 12. The point of engagement with rod 17 is made adjustable by means of a nut 26 on the free end. By manipulating the lever 12 in a counter clockwise direction the tie rod 17 is urged over toward the left, thereby swinging the 70 frame 13 outwardly against the tension of spring 15 and at the same time causing the pawl to slip over one or more teeth on the ratchet wheel 10. The outward position is illustrated in dotted lines in Fig. 4. Upon 75 release of the lever 12 (it may be actuated either by hand or foot) the spring 15 brings all elements back to normal position and at the same time actuates the gears 11 through pawl and ratchet mechanism 10. The roller 75 5 is rotated by frictional engagement with roller 4 when the pawl and ratchet operate the gears 11.

The operator feeds the filament lengths 19, preferably one by one, into a hopper 14, 95 and the hopper being trough-like in form the filaments readily arrange themselves longitudinally thereof and of the rollers, and when the frame 13 is actuated to open up the hopper the filament falls between the 100 rollers 4 and 5. On the return of the frame 13 the rollers are rotated as before described to crimp the filament 19 into a form similar to that designated at 20. The crimped filaments 20 slide down chute 21 into a suitable 105 receptacle (not shown) and are subsequently mounted on a lamp filament support, as shown in Fig. 5.

The crimping rollers 4 and 5 embody the Hughes invention above referred to, but 110

have certain improvements in addition. Each roller comprises a central shaft with a series of metal rings 22 closely fitting thereon. The metal rings serve as spacers 5 for the crimping rings or flanges 23, and the latter coöperate with the resilient facings 24 to shape the wire in accordance with Hughes invention. The flanges 23 preferably have serrated, knurled, or roughened 10 edges 25 for more securely gripping the filament length and thereby insuring transverse movement at every point of the filament length during the crimping operation. It was found that a smooth edge sometimes 15 permitted one end of the filament length to slip and hence lag behind the other end, resulting in nonuniform crimping.

Guards 27 are fixed below the rollers and adjacent thereto for gathering the crimped 20 filaments from the rollers and delivering them to the chute 21.

In accordance with the patent statutes, I have set forth one complete embodiment 25 of my invention, but it is understood that my invention is capable of assuming other forms than those illustrated and should not be restricted except as particularly pointed out in the attached claims.

What I claim and desire to secure by Letters Patent of the United States is:—

30 1. In an apparatus for shaping filament lengths, two coöperating crimping rollers, a hopper containing filament lengths located above said rollers, means for opening said 35 hopper to feed the filaments transversely between said rollers and a spring for returning said hopper to its closed position and simultaneously actuating said rollers.

2. In an apparatus for shaping filament 40 lengths, two coöperating crimping rollers, one having a resilient facing and the other coöperating crimping flanges arranged at right angles to the roller in combination with means for feeding the filaments trans- 45 versely of their lengths and actuating said rollers.

3. In an apparatus for shaping filament

lengths, two coöperating rollers, one having a resilient facing and the other having flanges arranged at right angles thereto co- 50 operating with grooves in said facing, in combination with means for feeding said filaments transversely of their lengths and actuating said rollers.

4. In an apparatus for shaping filament 55 lengths, two coöperating rollers having resilient facings and crimping flanges with serrated edges in combination with means for feeding the filament lengths transversely of their lengths and actuating said rollers. 60

5. In an apparatus for shaping filament lengths, a crimping roller in combination with a coöperating roller which is adjustable toward and away from said first named roller at least one of said rollers having a 65 resilient facing and means for feeding the filaments transversely of their lengths to and actuating said rollers.

6. In an apparatus for shaping wires, the combination of two coöperating rollers, at 70 least one of which has a resilient facing and at least one of which carries crimping means, and means for intermittently feeding a wire transversely of its length between said rollers and for actuating said rollers 75 after each feeding operation.

7. In an apparatus for shaping wires, two coöperating rollers, at least one of which has a resilient facing and at least one of which has crimping flanges, in combination with means for feeding a wire transversely of its length and for actuating said rollers. 80

8. In an apparatus for shaping wires, a crimping roller in combination with a co- 85 operating roller which is adjustable toward and away from said first named roller, at least one of said rollers having a resilient facing, and means for feeding the wires transversely of their lengths to and actuating said rollers. 90

In witness whereof I have hereunto set my hand this 6th day of May, 1916.

JAMES E. MARSHALL.
